AIR HEATER

Filed March 6, 1929

FIG. 1.

-14

FIG. 3.

Inventor:

Henry Lange
Monroe Miller

UNITED STATES PATENT OFFICE

HENRY LANGE, OF QUINCY, ILLINOIS, ASSIGNEE TO THE QUINCY STOVE MANUFACTURING COMPANY, OF QUINCY, ILLINOIS, A CORPORATION OF ILLINOIS

AIR HEATER

Application filed March 6, 1929. Serial No. 344,732.

The present invention relates to heaters, more particularly the air circulating type of heater comprising a stove and a casing surrounding same, of the general type disclosed 5 in my Patent No. 1,695,658, granted Dec. 18, 1928.

It has been the general practice to construct a circulating type of heater with an open top so that the greater amount of heat is directed 10 upwardly toward the ceiling of the room in which the heater is located. This has been found to be objectionable on account of the ruination of the wallpaper on the ceiling due to the heat and the depositing of dust, dirt 15 and other foreign matter on the paper.

It is the object of the present invention to provide a novel top construction for the casing or cabinet of an air circulating type of heater which will diffuse and distribute the 20 heated air both upwardly and horizontally, to avoid the objections of the open top type of heater, and to obtain a more efficient distribution of the heat in the room.

A further object is the provision of an air 25 heater casing or cabinet having a corrugated top and outlet apertures or openings so arranged as to obtain a desirable discharge of the heated air.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawing, wherein—

Figure 1 is a plan view of the improved 40 top construction for an air heater.

Fig. 2 is a side elevation thereof, portions being broken away and shown in section.

Fig. 3 is a sectional view on the line 3—3 of Fig. 2.

The top of the casing or jacket which 45 encloses the stove (not shown) may be of sheet metal or may be a casting, and is corrugated. The corrugations may extend from side to side or from front to rear of the casing. As 50 shown, the corrugations are of angular form,

but they may be of sinuous or other suitable shape.

The corrugations have the upper or outer portions 4, the lower or inner horizontal portions 5, and the vertical walls 6, forming the inner horizontal channels 7 and the outer horizontal channels 8.

The portions 4 and walls 6 are imperforate, and the portions 4 define the upper surface or top of the heater having the upwardly 55 opening channels 8. The portions 5 have apertures 9 therein through which the heated air may rise into and through the channels 8.

The front and rear walls 10 of the casing or cabinet overlap the walls 6 of the top at the edges of said top, while the side walls 11 have inturned flanges 12 at their upper edges on which the ends of the portions 5 are seated.

A top frame 13 of one or more parts surrounds the top and the upper ends of the 60 walls, and has an inturned lip or flange 14 at its upper edge seating on the portions 4 of the top.

The frame 13 has apertures 15 at the ends 65 of the inner channels 7, so that the heated air which is encouraged to flow upwardly into the channels 7 will discharge horizontally from the ends of the channels through the apertures 15.

The heated air is thus divided, part flowing 70 upwardly through the apertures 9 and channels 8 toward the ceiling, and part of the heated air flows from the channels 7 through the apertures 15. In this way a diffusion 75 of the heated air is obtained and a desirable 80 distribution of the heat is accomplished.

Having thus described the invention, what 85 is claimed as new is:

1. An air heater casing having a corrugated top with outer and inner channels and 90 having apertures for the upward flow of heated air into the outer channels.

2. An air heater casing having a corrugated top with outer and inner channels, said top having apertures for the upward flow 95 of heated air from within the casing into the outer channels, and the casing having provision for the discharge of heated air from the ends of the inner channels.

3. An air heater casing having a corrugated top with outer and inner channels and 100 having apertures for the upward flow of heated air into the outer channels.

863

gated top with inner and outer channels and a frame surrounding said top, said frame having outlet apertures registering with the ends of the inner channels.

4. An air heater casing having a corrugated top with inner and outer channels and a frame surrounding said top, said frame having outlet apertures registering with the ends of the inner channels, said top having apertures arranged for the upward flow of heated air from within the casing into the outer channels.

5. An air heater casing having a corrugated top with upper and lower portions and walls between them, said upper portions and walls being imperforate and the lower portions having apertures.

6. An air heater casing having a corrugated top with upper and lower portions and walls between them, said upper portions and walls being imperforate and the lower portions having apertures, the casing having provision for the discharge of air from the ends of the inner channels defined by said upper portions and walls.

7. An air heater casing having a corrugated top and a top frame surrounding same, said top having upper and lower portions and walls between them, said upper portions and walls being imperforate and the lower portions having apertures, said frame having outlet apertures registering with the ends of the inner channels defined by said upper portions and walls.

35. In testimony whereof I hereunto affix my signature.

HENRY LANGE.
